US00D762663S

(12) **United States Design Patent**
Lee et al.

(10) **Patent No.:** **US D762,663 S**
(45) **Date of Patent:** ** Aug. 2, 2016

(54) **DISPLAY SCREEN OR PORTION THEREOF
WITH GRAPHICAL USER INTERFACE**

(71) Applicant: **Samsung Electronics Co., Ltd.,**
Suwon-si (KR)

(72) Inventors: **Son-Young Lee**, Seoul (KR); **Ho Kim**,
Seoul (KR); **Ji-Yeon Kim**, Yongin-si
(KR)

(73) Assignee: **SAMSUNG ELECTRONICS CO.,
LTD.**, Suwon-Si (KR)

(**) Term: **14 Years**

(21) Appl. No.: **29/513,842**

(22) Filed: **Jan. 6, 2015**

(30) **Foreign Application Priority Data**

Sep. 2, 2014 (KR) 30-2014-0042734

(51) LOC (10) Cl. **14-04**

(52) U.S. Cl.

USPC **D14/485**

(58) **Field of Classification Search**

(57) **CLAIM**

The ornamental design for a display screen or portion thereof with graphical user interface, as shown and described.

DESCRIPTION

The FIGURE is a front view of a display screen or portion thereof with graphical user interface, showing our new design.

The dashed broken lines showing portions of the display screen or portion thereof with graphical user interface are for environmental purposes only and form no part of the claimed design.

1 Claim, 1 Drawing Sheet
